(Cl. 34—15)

To all whom it may concern:

Be it known that I, Donald E. Robinson, a citizen of the United States, residing at Rutherford, in the county of Bergen, State of New Jersey, have invented a new, original, and ornamental Design for a Toy Xylophone, of which the following is a specification, reference being had to the accompanying drawing forming part thereof, wherein:

Fig. 1 is a plan view of a toy xylophone showing my new design;

Fig. 2 is a side elevation thereof;
Fig. 3 is a sectional elevation, taken on lines
3—3 of Fig. 1;

Fig. 4 is a sectional elevation taken on lines
4—4 of Fig. 1.

I claim:

The ornamental design for a toy xylophone,
substantially as shown.

DONALD E. ROBINSON.
